ROBERT H. HAZELTINE, OF NEW YORK, N. Y.

FUEL TANK.

Application filed June 17, 1921, Serial No. 478,334. Renewed March 20, 1926.

My invention relates to devices for receiving a supply of liquid from a suitable source located at a level below the device and for supplying such liquid by gravity to an apparatus in which it is used, the power for conveying the liquid to the device being supplied by a suitable source of vacuum, and is particularly applicable to fuel tanks for motor vehicles in which a source of liquid fuel is located at a convenient low level, as for instance, the main fuel tank and a carburetor is supplied by gravity, the fuel tank being interposed between the two at a level higher than the main tank and carburetor and being operated by suction obtained by connecting the tank to the engine manifold.

In such devices, it is essential that the device embody the minimum number of movable parts and be of extreme simplicity and great ruggedness, and it is desirable that a suitable supply of liquid fuel be obtained for the carburetor at substantially constant pressure. My invention aims to provide an apparatus which will comply with these requirements in a simple and effective manner and shall be easy to construct and assemble.

In the drawings, I have shown,

In Fig. 1, a sectional view of a simple form of my improved device;

In Fig. 2, a sectional view taken on the line 2—2 of Fig. 1, showing the rotating or movable element of my device more in detail;

In Fig. 3, a sectional view of a more highly developed form of my invention;

In Fig. 4, a still more highly developed form of my invention; and

In Fig. 5, a perspective view of the rotor shown in section in Fig. 4.

In general my invention contemplates the delivery to a container, the position of which is properly selected with respect to the carburetor, of quantities of liquid by a pump, the movable element of which may be actuated by the suction of the engine or other suitable force. The pump used may take a variety of forms and may be rotating or reciprocating and be provided with driving means adapted to the character of the operating force. The specific form illustrated in the drawings comprises a rotating element or rotor divided into a plurality of compartments, which rotor is rotated by means of the suction of the engine due to

the successive introduction into the compartments of liquid under the influence of the vacuum, the rotor being turned to its discharge position by the weight of the liquid or by the combined weight of the liquid and its force of impact upon the rotor.

Thus in Fig. 1, I have shown a container 1, which may be of any suitable shape closed by a cover 2, through which an air vent 3 extends, venting the container 1 to the atmosphere. The liquid is supplied to the device by the pipe 4 and the pipe 5 is connected to the intake manifold of the engine, or to any other suitable source of suction.

Located in the cover 2 is a rotor 6 suitably mounted upon the stationary shaft 7 which is channeled as at 8 to communicate with the liquid supply pipe 4. The mounting is such as to secure the maximum freedom of rotation as by the use of ball bearings and the clearances between the rotor and the parts around it are as small as practicable in order to provide an efficient seal. The rotor 6 is divided into a plurality of compartments illustrated in the drawings as being four in number, 9, 10, 11 and 12, by means of suitable partitions. The outer and inner ends 13 and 14 respectively of the rotor partitions are thus formed in order to secure as tight a seal between the rotor and the stationary parts as possible, but it will be noted that it is not necessary to at any time close the orifice of the liquid supply inlet 8 and of the suction supply inlet 15. The rotor is preferably made in the form shown in section in Fig. 2 or in perspective in Fig. 5, by reference to which it will be seen that the periphery of the rotor is closed by peripheral walls 16 except at the center where the rotor registers with the discharge orifice formed at the bottom of cover 2.

It will be understood that the size of the rotor, the size of the fuel and suction pipes and the capacity of the container are proportioned with respect to the suction of the engine and its fuel requirements in the modification shown in Fig. 1 so that any variations in the relation of suction to fuel requirement which may be met with in the operation of the engine are compensated for by the liquid in the container 1. The modification shown in Fig. 1 is therefore particularly adapted to engines operating under constant load with a fixed throttle opening.

in which the fuel requirements and suction are relatively constant, although it is capable, if properly proportioned, to be effectively used in connection with engines operated over a wide range of throttle openings, fuel requirements, and load.

The operation of the device illustrated in Fig. 1 is as follows: Starting with the parts in the position shown in Fig. 1, the fuel is supplied from the pipe 4 and orifice 8 to the compartment 10, suction being maintained at pipe 5. When a quantity of fuel has been thus brought into compartment 10 sufficient to cause the rotation of the rotor, the rotor rotates past the fuel orifice 8 and the suction orifice 15, thus diverting fuel and suction into an adjacent compartment. The rotor continues to rotate until the contents of compartment 10 are discharged into the container 1 through the orifice 16 at the lower part of the cover 2 and the fuel is fed to its point of consumption through the outlet pipe 17 located at the bottom of container 1. The continued rotation of the rotor having put compartment 11 into position, for operation, the pumping operation described above is repeated.

It will be noted that in Fig. 1 no provision is made for stopping the action of the device in the event that the level of the liquid in container 1 rises to such a point as to prevent the rotation of the rotor, or that the rotor ceases to revolve for some other reason. In this event, if the parts were arrested in the position shown in Fig. 1 or in any other position in which both the fuel supply and suction ports were uncovered, the compartment in operation at that time might be filled with liquid until it covered the suction port and would thus be taken into the engine manifold through the suction line. To take care of this contingency, I have provided in Fig. 3, a means for shutting off the suction in the event of the filling of the compartment. Such means includes the provision of a chamber 18 in which is located a float 19 mounted upon a spindle 20, which carries a poppet valve 21 at its upper end and a piston valve 22 at its lower end. The source of suction is connected through the pipe 5 with the chamber 18 and the chamber 18 with the orifice 15, the remaining parts being the same as in the modification illustrated in Fig. 1. Orifice 15, however, opens into container 1, as at 23, as will be explained hereafter.

In the operation of Fig. 3, assuming the rotor to be arrested in the position illustrated, the continuance of the suction will cause the compartment 10 to fill to above the level of the orifice 15 and thereafter the chamber 18 will be partially filled with liquid, as will be understood. The rise in the level of the liquid in the chamber 18 will cause float 19 to rise, thereby shutting

off the suction by the seating of the poppet valve 21 and thus arresting the further flow of liquid. The rising of the float 19 will also cause piston valve 22 to register with the orifice 23 and will thus drain the chamber 18 into the tank 1, permitting the float to resume the position shown in Fig. 1 and the device to again become operative if the conditions are proper for operation. If they are not, the float 19 will again rise under the influence of the increase in level of the liquid in the chamber 18 and again shut off the suction until the conditions are right for continued operation.

In Fig. 4 I have illustrated a highly developed form of my invention, in which the atmosphere and suction are regulated both in response to variations in the level of the liquid in container 1 and to variations in the liquid in the chamber 18, the modification described in Fig. 3 illustrating simply the regulation of suction in response to variations of level in the chamber 18. In the modification of Fig. 4 a different form of rotor is used, there being no liquid supply through a hollow shaft, but the motor being mounted on trunnions 24 and the liquid being supplied through pipe 4 having an orifice 25 in the pump chamber of cover 2. There is also in the pump chamber the orifice 15, through which suction is supplied to the pump, which orifice is connected with chamber 18, as in the modification of Fig. 3.

Mounted upon the cover 2 is a valve housing 26 comprising two piston valves, one operated in response to variations in the level of the liquid in the container 1 through the instrumentality of float 27, bell crank 28, rod 29 and bell crank 30, and the other operated in response to variations in the level of the liquid in the container 1 through the instrumentality of float 31 and bell crank 32. The valve housing 26 contains three apertures, apertures 33 and 34 being for atmosphere and aperture 35 being for suction and therefore connected to pipe 5. Each of the pistons contain two apertures, the container piston apertures 36 and 37 and the chamber piston apertures 38 and 39, the operation of which will be hereafter described in detail. A drain valve, which may be in the form of a poppet valve 40 is arranged in the bottom of chamber 18 and is normally held in a closed position by spring 41, it being opened by the operation of lever 42 and stem 43. Suitable limiting stops to regulate the throw of the valve pistons may be provided.

The operation of the modification shown in Fig. 4 is as follows: Assuming the parts to be in the position shown in Fig. 4, suction is supplied through pipe 5, chamber 18 and orifice 15 to the pump, and liquid through pipe 4 and orifice 25. It will be noted that the position of the orifice 25 is so

arranged with respect to the pump that the force of impact of the liquid upon the rotor is used to assist in its rotation. Assuming the level in container 1 to rise to such an extent as to cause the movement of the float 27 to the dotted line position, the upper or container piston valve will be thrown to the dotted line position, thus throwing ports 35 and 36 out of registry and shutting off the suction and throwing ports 33 and 37 in registry, thus venting the compartment 18 to atmosphere. This will cause the interruption of the pumping operation and consequently of the supply of liquid to the container 1. If desired, a suitable lost motion, either at the junction of bell crank 28 and rod 29 or of rod 29 and bell crank 30, or bell crank 30 and the valve piston may be provided so that the operation of the container valve will be delayed. It will be understood that the pumping operation is the same as described in connection with the previous figures, the rotor compartments being filled with liquid and discharging into the container 1 through the port 16.

In the event of the stoppage of the rotor for any reason, the compartment being filled at the moment will be filled until the liquid flows through orifice 15 into chamber 18, thus raising the float 31. Assuming float 31 to be raised to the dotted line position, float 27 being at that time in the full line position, the container piston will be moved to the dotted line position under the influence of the variation of liquid level in the chamber 18, thus throwing ports 33 and 39 and 35 and 38 out of registry and ports 39 and 34 into registry. This, as will be seen, has the effect of cutting off the atmosphere at port 33, cutting off the suction at port 35 and venting the compartment 18 to atmosphere through ports 39 and 34. The rising of the float 31 also causes the arm 32 to engage the lever 42, throwing the poppet valve 40 downwardly against the tension of spring 41 and emptying the compartment 18 into container 1. This results in the dropping of float 31 and the restoration of the parts to the full line position. As in the modification shown in Fig. 3, if the condition of the rotor continues, the operation as described above will be repeated until the parts are in position for continued normal operation.

It will be understood that many modifications may be made in the specific device illustrated and described and I therefore do not wish to confine myself thereto.

What I claim is:

1. In a device of the kind described, means providing a plurality of compartments, means for successively subjecting said compartments to the action of a vacuum, means for supplying a liquid to said compartments a chamber communicating with said compart-

ments and means responsive to the liquid level in said chamber for cutting off the vacuum and connecting said chamber and compartment to the atmosphere.

2. In a device of the kind described, a container open to the atmosphere, a rotating member divided into a plurality of compartments, means for successively subjecting said compartments to the action of a vacuum during a predetermined angular movement of the rotating member, means for supplying a liquid to said compartments during said predetermined movement, means for emptying said compartments by the continued rotation thereof into the container, and means responsive to the liquid level in the container for cutting off the vacuum.

3. In a device of the kind described, a container open to the atmosphere, a rotating member divided into a plurality of compartments, means for successively subjecting said compartments to the action of a vacuum during a predetermined angular movement of the rotating member, means for supplying a liquid to said compartments during said predetermined movement, means for emptying said compartments by the continued rotation thereof into the container, and means operative upon the stopping of the rotative member whereby the vacuum is cut off to the functioning compartment and said compartment connected to the atmosphere.

4. In a device of the kind described, a rotating member divided into a plurality of compartments, means for successively subjecting said compartments to the action of a vacuum, means for supplying a liquid to said compartments, a chamber successively communicating with said compartments and means responsive to the liquid level in said chamber for cutting off the vacuum and connecting said chamber and compartment to atmosphere.

5. In a device of the kind described, a container open to the atmosphere, a movable pump member having a compartment, means for subjecting said compartment to the action of a vacuum during a predetermined movement of the movable pump member, means for supplying a liquid to said compartment during said predetermined movement, means for emptying said compartment by a continued movement thereof into the container and means responsive to the liquid level in the container for cutting off the vacuum.

6. In a device of the kind described, a rotating member divided into a plurality of compartments, means for successively subjecting said compartments to the action of a vacuum, means for supplying a liquid to said compartments, a chamber successively communicating with said compartments, means responsive to the liquid level in said chamber for cutting off the vacuum and connect-

ing said chamber and compartment to atmosphere, a container into which said compartments are adapted to empty and means responsive to the liquid level in said container for cutting off the vacuum from said compartment and chamber and for emptying said chamber into said container.

7. In a device of the kind described, a container open to the atmosphere, a housing mounted at the upper end thereof, a member divided into a plurality of compartments mounted to rotate within said housing, said housing being provided with a vacuum passage communicating with said rotating member and an opening permitting the emptying of said compartments into said container and being provided with a chamber communicating with said rotating member, means responsive to the level of liquid in the container for cutting off the vacuum and means responsive to the level of the liquid in the chamber for cutting off the vacuum in-

dependently of said first vacuum cutting off means.

8. In a device of the kind described, a movable pump member having a compartment, means for subjecting said compartment to the action of a vacuum, means for supplying a liquid to said compartment, a chamber communicating with said compartment, means responsive to the liquid level in said chamber for cutting off the vacuum and connecting said chamber and compartment to the atmosphere, a container into which said compartment is adapted to empty and means responsive to the liquid level in said container for cutting off the vacuum from said compartment and chamber and for emptying said chamber into said container.

In testimony whereof, I have signed my name to this specification this 14th day of June, 1921.

ROBERT H. HAZELTINE
